United States Patent Office

Des. 197,139
Patented Dec. 17, 1963

197,139

BRIEF CASE LOCK OR SIMILAR ARTICLE

Charles S. Gehrie, Montclair, N.J., assignor to Presto
Lock Co., Garfield, N.J., a limited partnership

Filed May 8, 1962, Ser. No. 70,032

Term of patent 14 years

(Cl. D50—7)

FIG. 1

FIG. 3

FIG. 1 is a top plan view of a brief case lock or similar article embodying my new design;

FIG. 2 is a side elevational view of the brief case lock or similar article shown in FIG. 1; and

FIG. 3 is a bottom end view of the brief case lock or similar article shown in FIG. 1.

I claim:

The ornamental design for a brief case lock or similar article, as shown.
